(57) **CLAIM**

The ornamental design for a triangular leg as shown and described.

DESCRIPTION

FIG. 1 is a perspective view of a triangular leg showing the new design in an environment of use;

FIG. 2 is a perspective view thereof, shown without its environment;

FIG. 3 is a front view thereof, the back view being a mirror image thereof;

FIG. 4 is a left-side view thereof;

FIG. 5 is a right-side view thereof;

FIG. 6 is a top view thereof; and,

FIG. 7 is a bottom view thereof.

Broken lines in the figures show portions of the triangular leg and its environment, neither of which form a part of the claimed design.

1 Claim, 7 Drawing Sheets
